UNITED STATES PATENT OFFICE.

JAMES A. SHERWOOD, OF PLAINWELL, MICHIGAN, ASSIGNOR OF ONE-HALF
TO JOHN W. GILKEY, OF SAME PLACE.

JEWELER'S DUST-BOX.

SPECIFICATION forming part of Letters Patent No. 320,593, dated June 23, 1885.

Application filed March 28, 1885. (No model.)

To all whom it may concern:

Be it known that I, JAMES A. SHERWOOD, a citizen of the United States, residing at Plainwell, county of Allegan, State of Michigan, have invented a new and useful Jeweler's Dust-Box, of which the following is a specification.

This invention has for its object certain improvements hereinafter described and claimed.

10 In the drawing, forming a part of this specification, is shown a perspective view of my new dust-box, parts being broken away, showing the internal construction and arrangement.

The wall inclosures of the box are shown at 15 B B, representing four sides. The other two sides opposite to each other are provided with covers D D, connected to the box by hinges a a, or otherwise, as desired. If preferred, the box may be provided with sliding covers running in grooves in the common manner. The doors are preferably made with a portion of them glass, C, or otherwise transparent, so as to see the contents.

20 The box is separated into two or more compartments by the partition P, the larger compartment being for large pieces of jewelry—such as the case and large parts of a watch—and the smaller compartment being designed for small pieces, such as the wheels and small 25 parts of the running mechanism of a watch, which might be injured by contact with the larger parts if all were in a single compartment. These compartments are centrally divided by a perforated partition, F, or grate of 30 any suitable nature. The partition F in the drawing consists of a metal plate provided with holes c c.

35 Sawdust or any like material commonly used by jewelers for drying the jewelry is shown 40 at R.

The doors D D may be fastened during the operation by any suitable catch, the latter not here shown.

45 The important peculiarity of my box as contrasted with dust-boxes heretofore used consists in the two compartments, having the central perforated partition for containing and treating under a single operation the large and small pieces of mechanism or jewelry separated 50 from each other.

In the operation, the parts of mechanism which the jeweler has cleaned, and which he desires to dry by agitating them in sawdust, are placed in the large and small compartments, together with the sawdust, above the 55 perforated plate or partition F. Then by shaking the box the sawdust sifts through the perforations c c, leaving the jewelry exposed and dry, ready to be removed from the box. When using the box again, it is turned the other 60 side up, and the jewelry placed among the sawdust through the other door, which will then be uppermost.

A packing may be used between the box and the covers to insure a tight joint to prevent 65 the escape of the fine sawdust. This in most cases will not be needed.

In the drawing strips of rubber V are shown embedded in the edges of the walls B B and the partition P, said rubber strips extending 70 a little above the edges, so that the covers D will press upon them when closed, thus forming a packing.

Having thus described my invention, what I claim as new, and desire to secure by Letters 75 Patent, is—

1. A jeweler's dust-box having separate compartments for different pieces of jewelry, said compartments being provided with a central perforated partition and with suitable covers, 80 substantially as set forth.

2. A jeweler's dust-box having separate compartments for different pieces of jewelry, two opposite sides of the box being provided with transparent inclosures, substantially as set 85 forth.

3. A jeweler's dust-box having separate compartments, doors or covers to said compartments, a packing between the doors and the wall inclosures, and a partition between the 90 compartments, substantially as set forth.

In testimony of the foregoing I have hereunto subscribed my name in presence of two witnesses.

JAMES A. SHERWOOD.
